SPOOL MOUNTING AND OPERATING MEANS

Pacific J. Thomas, Wyoming, Pa., assignor to U. S.
Textile Machine Company, Scranton, Pa., a
corporation of Pennsylvania

Application February 15, 1949, Serial No. 76,627

19 Claims. (Cl. 242—130)

1

This invention relates to textile and other machines provided with one or more yarn or strand receiving spools, bobbins, tubes, or other similar devices, and more particularly concerns the means for mounting and operating such yarn or strand receiving devices.

Textile machines, such as certain yarn winding and twisting machines of the type manufactured and sold by the U. S. Textile Machine Company, of Scranton, Pennsylvania, are provided with one or more decks of similar yarn winding and twisting units, each of which units comprises means for mounting and rotating the spools, or other similar devices, on which the yarn is wound. The spool mounting and rotation means of such units, are all alike, and are arranged so that the yarn receiving spools can be mounted in the machine, subjected to the yarn receiving operation, and then removed from the machine. The modernization of such machines, to increase their output capacity, has been found to involve various problems. For example, it has been found that when the operating or rotating speed of the yarn receiving spools is increased beyond a certain point, the spools develop a wobbling action of such magnitude that the frictional driving connection between the spools and the spool driving means is interrupted in sporadic manner. This detrimentally affects the uniformity of the yarn winding arrangement and action. Then too, increase in output capacity of these machines necessitates the inclusion of certain desirable labor and time saving features, such as spool mounting means arranged to permit quicker and easier insertion and removal of the spools, means operative to permit positioning of the spools so as to facilitate the work of the machine operator in overcoming the difficulties resulting from yarn breakage, etc., and means permitting the insertion of spools of different sizes or lengths so as to increase the usefulness of the machine.

One object of my invention is to provide a novel spool mounting device that can be readily embodied in machines of the referred to type and which solves the indicated modernization problems of such machines.

Another object is to provide such a device which has certain structural and functional features of advantage over the similar devices of the prior art.

A further object is to provide such a device which embodies a novel lengthwise extensible multi-section member which is rotatably mounted in such manner that rotational movement of the

2

member will effect axial shifting of a pair of spool-end supporting elements, toward and from each other, so as to hold or release spools of the same or different lengths.

5 An additional object is to provide such a device in which the spool-end supporting elements each have combined therewith a freely rotatable roller arranged so that the respectively combined elements and rollers are independently and 10 limitedly movable in parallel planes, and the rollers may contactingly engage frictional spool drive means, individually or simultaneously, thereby to maintain constant spool driving connection irrespective of any wobbling of the spool 15 during high speed operation of the latter.

It is also an object to provide such a device having novel latch means arranged to releasably maintain the said lengthwise extensible multi-section member in one of a plurality of 20 selective rotational positions, and novel resilient means arranged to urge axial movement of one the member sections relative to the other.

Another object is to provide such a device 25 which comprises a base, a sleeve fixedly mounted on the base and provided with a spiral slot, a tubular member rotatably mounted in said sleeve and provided with a longitudinal slot, a rod-like element having a section thereof slidably arranged within the tubular member, a pin secured to the side of said section of the rod-like element 30 in such manner as to project through the longitudinal slot of the tubular member and the spiral cam slot of the sleeve, an arm secured to the tubular member, an arm secured to the rod-like element, and spool-end supporting means on each of said arms.

Other objects are, to provide such a device in 35 which said pin is of determined lesser diameter than the width of the longitudinal slot of the tubular member, so as to afford limited turning movement of the tubular member relative to the rod-like element; in which a spiral spring is arranged within the tubular member so as to urge sliding movement of the rod-like element in one direction; and in which a latch is arranged to releasably maintain the tubular member in one of a plurality of selective rotational positions.

With these and other objects in view, which 40 will become more apparent from the following detailed description of one practical and illustrative form of the improvements shown in the accompanying drawings, the invention comprises the novel device, elements, features of construction and arrangement of parts in coopera- 45 50 55

tive relationship, as more particularly defined by the hereto appended claims.

In the drawings:

Figure 1 is a top plan view of one form of device embodying my invention, mounted on a frame member of a textile or other machine, and shows certain parts of the device in open, or spool receiving position.

Fig. 2 is a top plan view of the device shown in Fig. 1, and illustrates said certain parts in another position with a spool supported in readiness for having a yarn or other strand wound thereon.

Fig. 3 is a front elevational view of the device and spool arrangement as shown in Fig. 2, and additionally shows part of the spool rotating or drive means of the textile or other machine.

Fig. 4 is a side elevational view of the device as it appears when mounted on the machine frame member, in cooperative relation with the spool rotating means of the machine, as illustrated in Fig. 3.

Fig. 5 is a longitudinal sectional view, taken substantially as indicated by the arrows 5-5 in Fig. 2.

Fig. 6 is an elevational sectional view taken substantially as indicated by the arrows 6-6 in Fig. 2.

Fig. 7 is a detail elevational sectional view taken substantially as indicated by the arrows 7-7 in Fig. 2, and

Fig. 8 is a partial elevational and partial sectional view of certain parts of the device seen by looking in the direction of the arrow 8 in Fig. 2.

As previously indicated, the device of my invention may be embodied in a yarn winding machine, or some other machine, of the well-known type in which one or more yarn or strand receiving spools, bobbins, tubes, or other similar means, are arranged to be mounted and operated so as to have yarns or other strands wound thereon. Machines of this type are provided with such usual parts shown in the drawings as a frame member 1 and spool operating or rotating means 2, for properly mounting and operating a conventional spool unit, and it is to be understood that my device is designed so that it can be substituted in such machines for said units, in a manner requiring no changes in the construction and operation of the machine. In the present instance, the spool operating or rotating means comprises a pair of similar drive wheels 2^a, that are fixedly secured to a power driven shaft 2^b of the machine.

The form of my invention illustrated in the drawings generally comprises a bracket or base 3 provided with two similar integrally formed pinch-binding clamps 4 and a bearing 5; a separate sleeve 6 provided with a cam slot 7; a lengthwise extensible multi-section member generally indicated by the numeral 8; a pair of similar freely rotatable oppositely arranged members generally indicated by the numeral 9, that are carried by arms 10 and 11 in such manner as to function as rotatable supports for a standard or conventional type spool 12; and latch means generally indicated by the numeral 13.

The bracket or base 3 is secured to the frame member 1 by suitable means, such as by stud screws 14, and the sleeve 6 is held in fixed adjusted position by the pinch-binding clamps 4.

As more particularly illustrated in Fig. 5, the lengthwise extensible multi-section member 8 comprises a tubular member 15 having a longi-

tudinally extending slot 16, and a rod-like element comprising three integral parts of circular cross-section, each of which is of a different diameter and respectively marked 17, 17^a and 17^b. The parts 17^a and 17^b of the rod element are telescopically arranged in the tubular member 15 so as to be axially shiftable or slidable therein, and the part 17^a is of such diameter as to have an easy sliding fit along the inner surface of the tube 15. The outer surface of the tube 15 is of such diameter as to have an easy rotating fit within the sleeve 6, and the bearing 5 of the base member 3. Fixedly secured within the tube 15, by press fit, or otherwise, is a bushing 18. A spiral compression spring 19 is mounted in tensioned condition on the rod element part 17^b, between the bushing 18 and a freely rotatable adjusting nut 17^c, which is in threaded engagement with a threaded end portion of the rod element part 17^b, as clearly shown. Secured to the rod element part 17^a, so as to extend from the outer surface thereof, is a stud screw or pin 20, arranged so as to project through the longitudinal slot 16 of the tubular member 15 and the cam slot 7 of the sleeve 6. It is to be particularly noted that the pin 20 is of lesser diameter than the width of the longitudinal slot 16. This provides for a certain amount of play, or rotary movement between the tubular member 15 and the rod element comprising integral parts 17, 17^a and 17^b, and consequently permits the arms 10 and 11 and the members 9 secured thereto, to independently move in parallel planes. In other words, this arrangement permits the members 9, and therefore the spool ends in engagement therewith, to independently move in vertical direction, to a limited extent, during the time that the members 9 and drive wheels 2^a are in driving association. The importance of this feature will become apparent from the later description of the operation of my device.

As more particularly shown in Fig. 6, each of the members 9 comprises a freely rotatable, double ball bearing drive head of standard construction, which is rotatably mounted on a short shaft 21, having a threaded end portion extending through a side section of the respective arm 10 or 11 with which it is associated.

In each instance, the shaft 21 is secured in fixed position to its respective arm, by a nut 22, and a split lock washer 23 is interposed between the nut 22 and the arm to assure retention of the nut in locked position. Centrally secured to the inner rigid side wall of each of the freely rotatable drive heads, is a shouldered stud screw 24, the head of which is of such length and diameter as to snugly but easily fit into the outer ends of the bore of the spool 12. A split lock washer 24^a is interposed in each instance between the stud screw shoulder and the said rigid inner side wall of the drive head, to assure retention of the stud screw 24 in position. In order that the freely rotatable members 9 may not only support, but also have driving engagement with the ends of the spool 12, a gasket 25 of relatively soft rubber or the like, is fixedly secured in an indentation formed in the inner rigid side wall section of each of the drive heads, in such manner that one of the flat side surfaces of the gasket 25 will contactingly engage and will press against the outer flat surface of the spool end or flange 12^a, when the spool 12 is properly mounted on the members 9. Similarly, the peripheral surface section of the drive heads is formed of a material, such as rubber or the like, providing good frictional contact, so as to

assure good frictional driving connection between the members 9 and the drive wheels 2^a of the machine.

The rear end of the arm 10 is provided with an integral pinch-binding clamp section 10^a which is adapted to be fixedly secured in selective position along the length of the rod element part 17. The rear end of the arm 11 is similarly provided with an integral pinch-binding clamp section 11^a adapted to be fixedly secured to the tubular member 15, between the bearing 5 and one of the pinch-binding clamps 4 of the base member 3, as clearly shown in Fig. 5. The arms 10 and 11 are consequently alignedly secured in opposed adjustably spaced relation to the parts 15 and 17 of the lengthwise extensible member 8, in such manner that these parts are rotatable in unison about the center of the member 8, as indicated in Fig. 4. When the member 8 and arms 10 and 11 have been unitedly rotated so as to occupy the position indicated by the dot-and-dash lines "0" in Fig. 4, the spool 12 is supported by the freely rotatable members 9-9 in its operating position, and the members 9-9 are in driving connection with the wheels 2^a of the drive means 2 of the machine.

The latch means 13 is provided to releasably maintain the unitary structure comprising the arms 10 and 11, members 9, and the lengthwise extensible element 8, in certain of the positions indicated in full and in dot-and-dash lines in Fig. 4. The latch means 13 comprises a latch arm 27, which is rockably secured to the outer side of arm 11, by means of a stud screw 26, the rear end of which latch arm 27 is shaped to form a hook-like section 27^a, adapted to cooperate with two latch elements 28 and 29, integrally formed on the outer portion of the bearing 5. A spiral spring wire 30 is wound about the shank of the stud screw 26 (see Fig. 7), one end of which spring wire is anchored in an aperture extending through the side of arm 11 and the other end of which is turned about the latch arm 27 in such manner that the latch arm will be constantly urged by the spring wire 30 to effect engagement of the latch hook 27^a with the latch elements 28 and 29 on the bearing 5. Fixedly secured to the bearing 5 is a stud 31 directly in back of the latch hook section 27^a, which stud 31 functions as a safety lock element to prevent unintentional rearward rotational movement of the unitary structure comprising the arms 10 and 11, member 8 and members 9, without first operating or depressing the forward end of the latch arm 27.

Operation

Referring more particularly to Figs. 1 to 5 inclusive, the device of my invention is operated substantially as follows:

The forward end of the latch arm 27 is depressed so as to disengage the hook-like section 27^a thereof from the particular latch element 28 or 29 with which it is engaged, and this action will release the unitary structure comprising arms 10 and 11, members 9 and lengthwise extensible element 8, for turning or rotary movement about the longitudinal axis of the latter.

Assuming that the spool 12 has just completed its rotational yarn receiving action to form a completed yarn package, and the members 9 are still in engagement with the drive wheels 2^a, then the forward end of the latch arm 27 is depressed 70 and upward and rearward rotational swinging movement of the arms 10 and 11 can be carried out from their position indicated by the dot-and-dash representation thereof marked "0" in Fig. 4, to either the inoperative full line position thereof 75

as shown in Fig. 4, or the inoperative dot-and-dash position thereof marked "I" in Fig. 4. Rotational movement of the arms 10 and 11 to the full line position shown in Fig. 4, will result in continued engagement of the members 9 and spool 12 as shown in Figs. 2, 3 and 6. However, as the arms 10 and 11 are rotationally moved upwardly and rearwardly, from their full line position of Fig. 4 to the dot-and-dash line position "I," the extensible member 8 will be elongated, i. e., the rod element comprising the parts 17, 17^a and 17^b, will move to the right as seen in Fig. 5, thereby causing compression of spring 19 and moving the arm 10 laterally away from the arm 11. This elongating action of the member 8 is caused by travel of the pin 20 to the right, between and along the cam edges of the cam slot 7. Movement of the pin 20 will also take place in the longitudinal slot 16 of the tubular member 15, so that the arms 10 and 11 will be maintained in parallel aligned relation, except to the limited extent of the previously referred to play, or spacing, existing between the pin 20 and side edges of the slot 16. The said lateral separating movement of the arm 10, from the arm 11, will cause a corresponding separating movement of the members 9. When the position is reached that is indicated by the dot-and-dash lines "I," in Fig. 4, the arms 10 and 11, and consequently the members 9, will have become separated to an extent making it possible to withdraw the spool 12 from the stud screws 24. That is to say, the free ends of the stud screws 24 will have become separated by a distance which is greater than the distance between the outer surfaces of the spool flanges 12^a. When this rotational position of the arms 10 and 11 has been reached, the latch arm 27 may be released so that the hook-like section 27^a thereof may engage under the latch element 29, to hold the various unitary parts in the said position indicated by the dot-and-dash lines "I."

Having removed the filled spool 12 from between the stud screws 24, a new or empty spool can then be inserted therebetween, the forward end of the latch arm 27 depressed, and the arms 10 and 11 again swung to the position illustrated by the dot-and-dash lines "0" in Fig. 4, thereby to cause contraction of the member 8 so that the spool will be engaged by the studs 24 and members 9 as shown in Fig. 6, and again establish driving connection of the elements 9 with the driving wheels 2^a of the driving mechanism of the machine. The hook-like section 27^a of the latch arm 27 will then rest on top of the latch element 28 formed on the bearing 5, as indicated in Fig. 4. During the contracting movement of the member 8, the compression spring 19 functions to pull the rod element comprising parts 17, 17^a and 17^b, to the left, so that the part 17^a will slide lengthwise within the tubular member 15, and any existent free play or spacing between the pin 20 and cam slot 7 will be taken up, or this play will cause the members 9 to be pressed more tightly against the spool flanges 12^a by the spring action.

When it is desired to quickly move the spool 12 to an inoperative position, so as to permit the operator to repair a breakage in the yarn being wound on the spool, or for some other reason, it is merely necessary that the arms 10 and 11 be moved upwardly a sufficient distance to cause the hook-like part 27^a of the latch arm 27, to become engaged with the portion 28 of the bearing 5, as shown in full lines in Fig. 4. The drive

heads of the members 9 will then be disengaged from the drive wheels 2^a sufficiently to discontinue the driving action of the spool. Thereafter, that is when the yarn breakage has been repaired, the spool 12 may again be rotated as 5 before by simply depressing the latch arm 21 and permitting the arms 10 and 11, together with all therewith associated parts, to drop to their former position indicated by the dot-and-dash lines "0" in Fig. 4.

As previously indicated, the pin 20 is of lesser diameter, by a determined amount, than the space between the longitudinal edges of the slot 16. The play afforded by this arrangement, between pin 20 and the said edges of the slot 16, 15 permits limited relative rotary or turning movement of the rod element comprising integral parts 17, 17^a and 17^b, and the tubular member 15. Consequently, the arms 10 and 11, and the members 9 secured thereto, will have limited independent rotary or turning movement in parallel planes. This limited independent movement of the members 9 permits the spool 12 to carry out the characteristic wobbling action, which develops during high speed rotation or operation thereof, and at the same time assures that, during this action, the driving heads of the members 9 will be maintained in constant driving contact with the drive wheels 2^a of the machine, either individually or simultaneously. This feature is 20 highly important in effecting proper yarn winding action at high speed operation of the spool, since either one, or both of the members 9, will be in contact with the driving wheels 2^a, at all times, thereby providing smooth and uniform rotary operation of the spool 12.

When it is desired to set the device for receiving spools 12 that are of a different length, than the spool shown in the drawings, it is merely necessary to release the pinch-binding clamp 10^a at the rear end of the arm 10, and slide the latter on the rod part 17, toward or away from the arm 11, by the proper amount to accommodate the spool of different length. After this has been done, the pinch-binding clamp 10^a is again applied so that the arm 10 is fixedly secured to the rod part 17 at the new location or adjusted position.

Of course, the novel device and improvements herein specifically shown and described, can be changed and modified in various ways without departing from the invention disclosed, the scope of which is more particularly indicated by the hereto appended claims.

I claim:

1. A device of the character described comprising, a base, a telescopically lengthwise extensible and contractable multi-section member pivotally mounted on said base with its members concentrically arranged to the pivotal mounting so that rotational movement of the member will effect axial shifting of one of the member sections relative to the other, spool-end supporting means arranged on each of the member sections in opposed spool receiving relation, locking means arranged to positively maintain the multi-section member in a predetermined rotational position and a latch pivotally mounted and movable with said spool end supporting means for engagement and disengagement of said locking means.

2. A device of the character described comprising, a base, a telescopically lengthwise extensible and contractable multi-section member pivotally mounted on said base with its mem-

bers concentrically arranged to the pivotal mounting so that rotational movement of the member will effect axial shifting of one of the member sections relative to the other, spool-end supporting means arranged on each of the member sections in opposed spool receiving relation, locking means arranged to positively maintain the multi-section member in one of a plurality of selective rotational positions and a latch pivotally mounted and movable with said spool end supporting means for engagement and disengagement of said locking means.

3. A device of the character described comprising, a base, a lengthwise extensible multi-section member rotatably mounted on said base and arranged so that rotational movement of the member will effect axial shifting of one of the member sections relative to the other, spool-end supporting means arranged on each of the member sections in opposed spool receiving relation, latch means arranged to releasably maintain the member in determined rotational position, and means determining the extent of release movement of the latch means so as to permit rotational movement of the member.

4. A device of the character described comprising; a base; a lengthwise extensible multi-section member rotatably mounted on said base and arranged so that rotational movement of the member will effect axial shifting of one of the member sections relative to the other; means arranged so that the member sections are limitedly turnable relative to each other; and a pair of freely rotatably spool-end engaging elements 30 35 respectively secured to the member sections in opposed spool receiving relation, which elements are adapted to contactingly engage rotational drive means independently or simultaneously during rotational yarn receiving action of the spool.

5. A device of the character described comprising; a base; a lengthwise extensible multi-section member rotatably mounted on said base and arranged so that rotational movement of the member will effect axial shifting of one of the member sections relative to the other; means arranged so that the member sections are limitedly turnable relative to each other; and a pair of freely rotatable spool-end engaging elements 45 50 respectively secured to the member sections in opposed spool receiving relation, which elements are adapted to contactingly engage rotational drive means independently or simultaneously during rotational yarn receiving action of the spool; and latch means arranged to releasably maintain the member in determined rotational position.

6. A device of the character described comprising, a base, a lengthwise extensible multi-section member rotatably mounted on said base and arranged so that rotational movement of the member will effect axial shifting of one of the member sections relative to the other, means arranged so that the member sections are limitedly turnable relative to each other, a separate freely rotatable spool-end engaging element secured to each of the member sections, and means arranged so that one of the elements may be adjustably secured in selected position along a lengthwise portion of one of the member sections.

7. A device of the character described comprising, a base, a lengthwise extensible multi-section member rotatably mounted on said base and arranged so that rotational movement of the member will effect axial shifting of one of the member

sections relative to the other, means arranged so that the member sections are limitedly turnable relative to each other, a separate freely rotatable spool-end engaging element secured to each of the member sections, means arranged so that one of the elements may be adjustably secured in selected position along a lengthwise portion of one of the member sections, and latch means arranged to releasably maintain the member in one of a plurality of selective rotational positions.

8. A device of the character described comprising; a base; a sleeve fixedly mounted on the base and provided with a spiral cam slot; a tubular member rotatably mounted in said sleeve and provided with a longitudinal slot; a rod-like element having a section thereof slidably arranged within the tubular member; a pin secured to the side of said section of the element in such manner as to project through the longitudinal slot of the tubular member and the spiral cam slot of the sleeve; an arm secured to the tubular member; an arm secured to the rod-like element; and spool-end supporting means on each of said arms.

9. A device of the character described comprising; a base; a sleeve fixedly mounted on the base and provided with a spiral cam slot; a tubular member rotatably mounted in said sleeve and provided with a longitudinal slot; a rod-like element having a section thereof slidably arranged within the tubular member; a pin secured to the side of said section of the element in such manner as to project through the longitudinal slot of the tubular member and the spiral cam slot of the sleeve; an arm secured to the tubular member; an arm arranged to be connected in selective position along a lengthwise portion of the rod-like element; and spool-end supporting means on each of said arms arranged in opposed spool receiving relation.

10. A device of the character described comprising; a base; a sleeve fixedly mounted on the base and provided with a spiral cam slot; a tubular member rotatably mounted in said sleeve and provided with a longitudinal slot; a rod-like element having a section thereof slidably arranged within the tubular member; a pin secured to the side of said section of the element in such manner as to project through the longitudinal slot of the tubular member and the spiral cam slot of the sleeve; an arm secured to the tubular member; an arm secured to the rod-like element; and freely rotatable spool-end supporting and revolving means on each of said arms arranged to be brought into frictional driving connection with certain rotational driving means of a textile machine.

11. A device of the character described comprising; a base; a sleeve fixedly mounted on the base and provided with a spiral cam slot; a tubular member rotatably mounted in said sleeve and provided with a longitudinal slot; a rod-like element having a section thereof slidably arranged within the tubular member; a pin of determined lesser diameter than the width of the longitudinal slot secured to the side of said section of the element in such manner as to project through the longitudinal slot of the tubular member and the spiral cam slot of the sleeve; an arm secured to the tubular member; an arm secured to the rod-like element; and freely rotatable spool-end supporting means on each of said arms arranged in opposing spool receiving relation.

12. A device of the character described comprising; a base; a sleeve fixedly mounted on the base and provided with a spiral cam slot; a tubu-

lar member rotatably mounted in said sleeve and provided with a longitudinal slot; a rod-like element having a section thereof slidably arranged within the tubular member; a pin of determined lesser diameter than the width of the longitudinal slot secured to the side of said section of the element in such manner as to project through the longitudinal slot of the tubular member and the spiral cam slot of the sleeve; an arm secured to the tubular member; an arm arranged to be connected in selective position along a lengthwise portion of the rod-like element; and freely rotatable spool-end supporting and revolving means on each of said arms arranged to be brought into frictional driving connection with certain rotational driving means of a textile machine.

13. A device of the character described comprising; a base; a sleeve fixedly mounted on the base and provided with a spiral cam slot; a tubular member rotatably mounted in said sleeve and provided with a longitudinal slot; a rod-like element having a section thereof slidably arranged within the tubular member; a pin secured to the side of said section of the element in such manner as to project through the longitudinal slot of the tubular member and the spiral cam slot of the sleeve; an arm secured to the tubular member; an arm secured to the rod-like element; spool-end supporting means on each of said arms; and latch means arranged to releasably maintain the tubular member in one of a plurality of selective rotational positions.

14. In a textile apparatus the combination of, a yarn receiving spool, a pair of opposed freely rotatable spool-end engaging members, means arranged so that the members are independently movable in parallel planes, and rotational drive means arranged to be contactingly engaged by said members individually or simultaneously during rotational yarn receiving action of the spool.

15. In a textile apparatus the combination of, a yarn receiving spool, a lengthwise extensible multi-section member arranged so that rotational movement of the member will effect axial shifting of one of the member sections relative to the other, a pair of opposed freely rotatable spool-end engaging elements, means securing each of said elements to one of the member sections, means arranged so that the member sections are limitedly turnable relative to each other, and rotational drive means arranged to be contactingly engaged by said elements individually or simultaneously during rotational yarn receiving action of the spool.

16. In a textile apparatus the combination of, a yarn receiving spool, a lengthwise extensible multi-section member arranged so that rotational movement of the member will effect axial shifting of one of the member sections relative to the other, a pair of opposed freely rotatable spool-end engaging elements, means securing each of said elements to one of the member sections, means arranged so that the member sections are limitedly turnable relative to each other, latch means arranged to releasably maintain the member in one of a plurality of selective rotational positions, and rotational drive means arranged to be contactingly engaged by said elements individually or simultaneously during rotational yarn receiving action of the spool.

17. In a textile apparatus the combination of, a yarn receiving spool, a lengthwise extensible multi-section member arranged so that rotational movement of the member will effect axial shift-

11

ing of one of the member sections relative to the other, a pair of opposed freely rotatable spool-end engaging elements, means securing one of the elements in fixed relation at one end of said member, means arranged to afford selective positional securing of the other element along a lengthwise portion at the opposite end of the member, means arranged so that the member sections are limitedly turnable relative to each other, and rotational drive means arranged to be contactingly engaged by said elements individually or simultaneously during rotational yarn receiving action of the spool.

18. In a textile apparatus the combination of, a yarn receiving spool, a lengthwise extensible multi-section member arranged so that rotational movement of the member will effect axial shifting of one of the member sections relative to the other, a pair of opposed freely rotatable spool-end engaging elements, means securing one of the elements in fixed relation at one end of said member, means arranged to afford selective positional securing of the other element along a lengthwise portion at the opposite end of the member, means arranged so that the member sections are limitedly turnable relative to each other, latch means arranged to releasably maintain the member in one of a plurality of selective rotational positions, and rotational drive means arranged to be contactingly engaged by said elements individually or simultaneously dur-

12

ing rotational yarn receiving action of the spool.

19. A device of the character described comprising; a base; a sleeve fixedly mounted on the base and provided with a spiral cam slot; a tubular member rotatably mounted in said sleeve and provided with a longitudinal slot; a rod-like element having a section thereof slidably arranged within the tubular member; a pin secured to the side of said section of the element in such manner as to project through the longitudinal slot of the tubular member and the spiral cam slot of the sleeve; an arm secured to the tubular member; an arm secured to the rod-like elements; spool-end supporting means on each of said arms, and resilient means within the tubular member arranged to urge sliding movement of the rod-like element in one direction.
